RAZOR BLADE SHARPENER

Filed March 15. 1928

UNITED STATES PATENT OFFICE

WILSON J. BREAUX, OF NEW ORLEANS, LOUISIANA

RAZOR-BLADE SHARPENER

Application filed March 15, 1928. Serial No. 261,960.

My invention relates to improvements in razor blade sharpeners, and is more especially intended for use in sharpening blades of safety razors. In ordinary practice, these 5 are generally used until they become dull, and then are thrown away, but the herein described invention is intended to provide a cheap, simple and efficient apparatus which may be used for re-sharpening such blades, or, if desired, for sharpening ordinary razor 10 blades; but it is more especially intended for use in connection with safety razor blades, since these are more commonly used and more conveniently sharpened in an apparatus of 15 the character described.

According to my invention, the razor blade may be drawn longitudinally over a stone or sharpening pad, and at the same time will be automatically given a transverse movement 20 while the apparatus provides for conveniently turning over the razor blade at each end of the stroke.

My invention will be more fully understood after reference to the accompanying drawings, in which like parts are indicated by similar reference symbols throughout the several views, and in which

Figure 1 is a plan view of the complete apparatus in use.

Figure 2 is a side elevation of the device with the handle omitted for the sake of clearness in the drawings.

Figure 3 shows a section along the line 3—3 of Figure 1, and looking in the direction of the arrows.

Figure 4 shows a section along the line 4—4 of Figure 2, and looking down, parts being shown in elevation.

Figure 5 is a sectional elevation of the sliding frame and handle, on which the razor blade is carried in the operation of sharpening same, and

Figure 6 is a detail view showing the razor blade and its holder, and the parts being shown in full lines for movement in one direction, and in dotted lines for movement in the reverse direction.

A represents a housing block hereinafter called a holder. For convenience of manipulation, the holder may be provided with a

handle *a*. This holder is provided with a socket *a'*.

The stone or pad B, on which the razor is sharpened, is held in such a way as to project above the top of the holder, as shown in Figures 2 and 3.

Secured beneath the holder is the base block D which is spaced from the holder, as by the transverse strips C and C' secured to the base block by means of the nails E or any other convenient way.

By this arrangement, an open slot is left between the holder and the base block.

The base block D is provided with guide ways D' and D² preferably re-inforced with metal, and may be secured to the base block in any convenient way as by means of the nails E, see Figure 4. These guide channels D' and D² are divergent as shown.

F represents the sliding frame carrying the razor blade to be sharpened, which sliding frame is operated by the handle F' revolvably connected thereto in any convenient way; as shown, for instance, in Figure 5, in which Figure G represents a pin secured in the handle by means of the cross pins g, and provided with a squared portion g' adapted to engage the pinion H which is held against turning on pin G. This pin G is journaled as at g² at one end of the sliding frame.

The sliding frame F has one end flanged upwards as at f to form a journaled bearing for one end of the shaft L, and the other end f' is also flanged upwards and bent over on itself as at f² to form a casing for the block f³ shown as at the left of Figure 5. Journaled at this end of the casing are the idler I and the pinion K carried by the end of the shaft L. Thus the rotation of the handle F' through an angle will cause the shaft L to be also rotated through an angle.

The bottom of the sliding frame carries a pin f⁴ preferably carrying an anti-friction roller f⁵, which roller engages in the guide ways D' and D², and imparts a transverse motion to the sliding frame as it is moved longitudinally, as will be hereinafter described.

The shaft L is flattened as at l, see Figure 3, to engage the blade holder M which is in the form of a clip held against turning on

said shaft, and which holds firmly in place the razor blade N which is to be sharpened.

The operation of the device is as follows:

- 6 The operator grasps the handle *a* of the holder with his left hand, and with his right hand grasps the handle *F'* of the sliding frame *F*, and turns this handle so that the gears *H*, *I* and *K* are rotating the shaft *L*, so that the blade *N* will bear on the surface of 10 the sharpening element *B*. This element, as before said, may be of stone, a leather pad, with or without abrasive material, or any other sharpening element which may be desired to use in connection with the holder.
- 15 Bearing with the proper pressure on the top of the sharpening element, as shown in Figure 1, and moving the traveling frame to the right of said figure, the roller γ^0 engaging in the grooves *D'* and *D²* will cause the traveling frame to move transversely of the sharpening element, at the same time it is moving longitudinally of said element, thus sharpening the edge of the blade from one side. When 20 the traveling frame has been moved as far as possible in one direction, turn the handle *F'* so as to shift the razor blade from the position shown in full lines in Figure 6 to that shown in dotted lines in said figure, and move the traveling frame in the opposite direction.
- 25 During this movement, the opposite side of the razor blade will be sharpened. Of course, in the operation of the device, the razor blade should be pressed down upon the abrasive surface with sufficient force to secure the desired abrasive effect.

A few vibratory movements of the traveling frame, if same be properly manipulated, will soon put the desired edge on the razor blade.

- 40 The razor blade may be conveniently inserted in the holder and removed therefrom by prying apart the jaws of the holder, which may be done by inserting a tapered awl not shown.

45 While I have shown a clip for holding the razor blade in place on the shaft *L*, any other suitable means may be used for this purpose, if desired. While I have shown one embodiment of the invention in its preferred form, 50 it will be obvious that various changes in the construction, combination and arrangement of parts might be made, which could be used without departing from the spirit of my invention, and I do not mean to limit the invention to such details, except as particularly pointed out in the claims.

Having thus described my invention, what I claim and desire to secure by Letters Patent of the United States is:

- 60 1. A hand razor blade sharpener comprising a handle and a housing block projecting forwardly therefrom, said block being provided with a recessed upper face and a plane lower face, an abrading block held in the recess in the upper face, a base block mounted 65

below the housing block, transverse spacing strips interposed between the ends of said housing block and said base block and spacing the two apart, said base block having a V-shaped groove in its upper surface, a blade holding frame provided with a cross bar projecting through the space and between said housing block and said base block, and slideable both longitudinally and laterally in said space, said frame having a projection engaging in said groove, a rotatable blade clamp carried by said frame, a handle rotatable attached to said frame, and means actuated by rotating said handle for rotating said clamp. 70

2. A hand razor blade sharpener comprising a handle and a housing block projecting forwardly therefrom, said block being provided with a recessed upper face and a plane lower face, an abrading block held in the recess in the upper face, a base block mounted below the housing block, transverse spacing strips interposed between the ends of said housing block and said base block and spacing the two apart, said base block having a V-shaped groove in its upper surface, a blade holding frame provided with a cross bar projecting through the space and between said housing block and said base block, and slideable both longitudinally and laterally in said space, said frame having a projection engaging in said groove, a rotatable blade clamp carried by said frame, a handle rotatably attached to said frame, and gearing carried by said frame, and actuated by rotating said handle for rotating said clamp. 75
